OVERHEAD GARAGE DOOR

Robert George Kuehner, Detroit, Mich., assignor
of one-half to Robert Albert Kuehner, Detroit,
Mich.

Application November 20, 1943, Serial No. 511,125

3 Claims. (Cl. 160—185)

This invention relates to new and useful improvements in garage doors and more particularly to the overhead opening type.

The principal object of the present invention is to provide an improved garage door, which by a simple movement can be elevated to an out-of-the-way position.

Another important object of the invention is to provide a folding overhead garage door which is counter-balanced in such a way as to make the effort necessary in opening the door almost unnoticeable.

Other objects and advantages of the invention will become apparent to the reader of the following description.

In the drawings—

Figure 1 represents a front elevational view of the door.

Figure 2 is a fragmentary vertical section taken on the line 2—2 of Figure 1.

Figure 3 is a fragmentary vertical sectional view taken also substantially on the line 2—2 of Figure 1, but showing the door in partly folded position.

Figure 4 is a vertical sectional view also taken substantially on the line 2—2 of Figure 1, but showing the door in fully opened position.

Figure 5 is an enlarged fragmentary detailed sectional view taken on the line 5—5 of Figure 3.

Figure 6 is a fragmentary vertical sectional view through one of the slides and channeled guides.

Figure 7 is a fragmentary perspective view showing the lower portion of one of the channeled guides.

Figure 8 is a fragmentary detailed sectional view between the door frame and door showing the pivot therefor.

Referring to the drawings wherein like numerals designate like parts, it can be seen that numeral 5 denotes a garage having a door frame made up of side portions 6, 6 and a top portion 7. Numeral 8 generally refers to the improved door which consists of an upper section 9 and a lower section 10, these sections being hingedly secured together as at 11.

Suitable handles or the like 12 are provided on the lower outside portion of the section 10, and this section of the door has laterally disposed pintles 13 which swivelly connect to blocks 14, slidably disposed within the lower portion of a vertically disposed and channeled guide 15. The lower portion of each of these guides 15 has a laterally disposed member 16 apertured to receive a pivot element 17 which is disposed into the corresponding frame side portion 6.

The upper section 9 has laterally disposed pintles 18 on which swivelly mounted slides 19 are

provided and these slides also operate in the channeled guide 15, as in the manner shown in Figure 6.

At the upper edge of the door section 9 is a counterweight, which may be a box 20 filled with some suitable heavy material 21.

The lower portion of this box 20 has a metal socket 22 at each end thereof to receive a pintle 23 projecting from a supporting plate 24 suitably secured as at 25 to the corresponding frame side portion 6. Thus the upper portion of the door section 9 is fixed as far as being movable in a vertical direction, however, the upper section is allowed to swing to the extent shown in Figure 4.

Obviously, a slight pressure at the hinged connection between the door sections 9, 10 will move the sections to substantially the position shown in Figure 3, after which a pull upwardly on the handles 12 will bring the door sections to the elevated positions shown in Figure 4 in a quick and substantially effortless operation.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

30. 1. A garage door comprising a door proper divided into a pair of sections hingedly secured together, a pair of channeled guides one at each side of the door, pintles projecting laterally from the door sections and slides on the pintles riding in the channeled guides, and counterbalancing means at the upper portion of the upper section.

35. 2. A garage door comprising a door proper divided into a pair of sections hingedly secured together, a pair of channeled guides one at each side of the door, pintles projecting laterally from the door sections and slides on the pintles riding in the channeled guides, and counterbalancing means at the upper portion of the upper section, said channeled guides being swingably supported at their lower end portions.

40. 3. A garage door comprising a door proper divided into a pair of sections hingedly secured together, a pair of channeled guides one at each side of the door, pintles projecting laterally from the door sections and slides on the pintles riding in the channeled guides, and counterbalancing means at the upper portion of the upper section, and means for swingably supporting the upper portion of the upper section along with its counterbalancing means, said guides being swingably supported at their lower end portions.

ROBERT GEORGE KUEHNER.
